CAR COUPLER

William J. Metzger, Cleveland, Ohio, assignor to
National Malleable and Steel Castings Company, Cleveland, Ohio, a corporation of Ohio

Application December 12, 1941, Serial No. 422,656

3 Claims. (Cl. 213—152)

This invention relates to car couplers and more particularly to a construction that will prevent pinching the lock between the knuckle tail and the coupler head when it is desired to raise the lock during uncoupling.

In uncoupling two cars it is customary to give the couplers a light buffing blow or force the buffing surfaces on the knuckles and head together by means of a locomotive so as to relieve the pressure of the knuckle tails against the locks and permit the lock of either coupler to be raised. It has been found, however, on couplers having wedge locks and on couplers in which the clearance for the lock in the lock chamber is small, that this procedure actually increases the pressure of the knuckle tail on the lock and makes the uncoupling operation very difficult. It is therefore an object of the present invention to provide means for preventing the lock from being pinched in the coupler head when buffing stresses are placed on the knuckle. Another object is to provide adjustable means on the coupler for preventing pinching of the lock when the coupler knuckle is subjected to a buffing force and for controlling the amount of closing of the knuckle.

In the drawings:

Figure 1 is a horizontal sectional view of a coupler which does not embody the invention, illustrating the manner in which the lock may be pinched in the coupler head.

Figure 2 is a horizontal sectional view of a coupler embodying the invention.

Figure 3 is a partial vertical sectional view, taken on line 3—3 of Figure 2.

Figure 4 is a fragmentary sectional view of a modification.

Figure 5 is a horizontal sectional view showing another embodiment of the invention; and

Figure 6 is a partial vertical sectional view, taken on line 6—6 of Figure 5.

Figure 1 illustrates a knuckle tail and coupler side wall construction in use on the railroads of the United States at the present time. It will be observed that the knuckle 10 has a curved surface 11 on the rear of the knuckle tail which is engageable with curved surface 12 on side wall 13 of the coupler head. In couplers provided with a wedge lock, such as the A. A. R. Tight Lock coupler, surfaces 11 and 12 are forced into engagement by the lock and pivotal movement of the knuckle is thereby prevented. However, some clearance is present between the knuckle pin 9 and the pin openings in the knuckle and coupler head which allows a slight

amount of longitudinal movement of the knuckle relative to the coupler head. If two cars fitted with couplers of this construction are buffed together to relieve the tension on the knuckles which were previously in draft, the buffing blow will move the knuckle rearwardly, causing surface 11 to slide along surface 12. This sliding movement, however, will result in the knuckle tail being moved laterally towards the lock, thus forcing the latter into tighter engagement with wall 14 of the coupler head and making it difficult if not impossible to raise the lock to unlock the coupler.

The present invention has as its object a construction that will prevent pinching of the lock between the knuckle tail and the coupler head during buffing of the coupler. Referring to Figures 2 and 3, the coupler head 15 has a pivoted knuckle 16 and a lock 17. The knuckle tail 18 has a lock engaging face 19 extending parallel to the longitudinal center line a—a of the coupler. Lock 17 has a surface 20 on one side in engagement with face 19 and a surface 21 on its opposite side, also parallel to the center line of the coupler and in engagement with surface 22 of the adjacent wall of the coupler. Surfaces 19 and 20 are at an angle to the vertical so that as the lock moves downwardly into locking position surface 23 of the knuckle tail is forced into engagement with surface 24 on the inner side of wall 25 of the coupler. Surfaces 23 and 24 are also parallel to the longitudinal center line of the coupler. It will be observed that there is clearance between the rear surface 26 of the knuckle tail and the coupler wall directly to the rear thereof. A slight amount of clearance is also shown between the knuckle pivot pin 27 and the pin receiving openings 28 in the knuckle and coupler head. This latter clearance is provided to enable proper fitting of the parts and permits a slight amount of movement of the knuckle longitudinally of the coupler head. Since each of the surfaces 19, 20, 21, 22, 23 and 24 is parallel to the longitudinal center line of the coupler, the knuckle, if it moves rearwardly during a buffing blow, will move in a direction parallel to the center line and will not move laterally, hence the pressure on the lock will not be increased. Although vertical surface 24 is shown parallel to the longitudinal center line, it will be clear that by positioning the surface at an angle to this position, as surface 29 in Fig. 4, the knuckle during buff will not be moved laterally against the lock. Surface 30 on the knuckle will of course be correspondingly positioned.

My invention is also adapted for use with cou-

plers having vertical locking faces on the knuckle and lock instead of the sloping surfaces 19 and 20 of Figures 2 and 3, particularly where the clearance between the locking surfaces is small and the lock is apt to bind as previously mentioned. This is illustrated in Figures 5 and 6, wherein surfaces 32 on the lock and 33 on knuckle tail 34 are vertical and parallel to the longitudinal center line $b-b$ of the coupler and have a slight clearance therebetween. Also parallel to the center line are surface 35 of the coupler in engagement with the lock and side surface 36 of the knuckle tail. In place of an integral surface or seat on the coupler for engagement with surface 36 of the knuckle tail, as shown in the previous embodiment, there is provided a removable seat 37 having its vertical surface 38 parallel to the center line. Seat 37 has a threaded portion 39 extending through the side of the coupler and is secured thereto by means of a nut 40. Since all of the engaging surfaces are parallel to the longitudinal center line, as in the embodiment shown in Figures 2 and 3, upon the subjection of the knuckle to a buffing force the knuckle tail will not be moved laterally so as to pinch the lock between surface 35 on the coupler and surface 33 on the tail. As the clearance about knuckle pin 41 in the knuckle and coupler head is taken up in buff, the knuckle moves bodily rearwardly, guided by surface 38, and there is no tendency of the knuckle tail to move laterally against the lock and prevent its being raised to unlocked position. The use of removable seat 37 facilitates the machining operations on the coupler head necessary to proper fitting and operation of the knuckle and lock when assembled in the coupler. In addition, the purpose of the removable seat is to provide easier initial adjustment of the amount of closing of the knuckle as well as adjustment thereof after the coupler has been in service for some time. This adjustment is effected by the use of a shim 42 between seat 37 and the coupler side wall. Thus in the case of a new coupler, if after assembly the knuckle closes a greater amount than normal or does not close enough, the proper closing of the knuckle may be obtained by varying the thickness of the shim. Likewise, when the coupler knuckle as a result of service closes too much, the addition of the proper size shim will remedy this condition. It is of course to be understood that removable seat 37 is applicable equally well to a coupler having a wedge lock construction, as shown in Figures 2 and 3. In fact, it is particularly advantageous to use this adjustable seat in the latter coupler due to the

closer tolerances required in the machining of a coupler head using the tapered lock. Consequently, any variations from normal in the amount of closing of the knuckle may be readily compensated by means of the shims.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A car coupler having a pivoted knuckle, said knuckle having a tail adapted to move to a position adjacent a side wall of the knuckle head upon pivoting of the knuckle to closed position, and normally immovable abutment means on said side wall adapted to be engaged by said tail upon closing of said knuckle, said means being adjustable in a direction laterally of the coupler to limit the amount of closing of the knuckle.

2. A car coupler having a pivoted knuckle, said knuckle having a tail adapted to move to a position adjacent a side wall of the knuckle head upon pivoting of the knuckle to closed position, and normally immovable abutment means on said side wall adapted to be engaged by said tail upon closing of said knuckle, said means comprising a seat member, shims interposed between the latter and said wall and means for releasably securing said seat and shims to said wall.

3. A car coupler having a pivoted knuckle adapted to move a slight amount longitudinally of the coupler when in locked position, said knuckle having a tail adapted to move to a position adjacent a side wall of the coupler head when the knuckle is pivoted to closed position, said tail having faces thereon parallel to the longitudinal center line of the coupler when the knuckle is in closed position, a vertically movable lock member having sides parallel to said center line, said member being adapted to be received between one of said tail faces and another side wall of the coupler head to lock said knuckle in closed position, and laterally adjustable abutment means on said side wall adjacent said tail having a vertical surface parallel to said center line and adapted to engage the other of said tail faces when said knuckle is subjected to a buffing force, said abutment means being normally immovable and adapted to guide said knuckle when the latter is in buff to preclude lateral movement of said tail against said lock member.

WILLIAM J. METZGER.
